UNITED STATES PATENT OFFICE.

ALBERT B. JOHNSON, OF HARTFORD, CONNECTICUT.

SWIMMER'S FOOT AID.

Application filed August 23, 1923. Serial No. 659,016.

To all whom it may concern:

Be it known that I, ALBERT B. JOHNSON, a citizen of the United States, residing at Hartford, in the county of Hartford and State of Connecticut, have invented certain new and useful Improvements in Swimmers' Foot Aids, of which the following is a specification.

My invention relates to improvements in swimmers' foot aids in the form that is adapted to be positioned at the bottom of the foot of the swimmer and that operates responsive to the usual swimming strokes and by means in the form of expandible and collapsible wing structure to provide a relatively extended contacting area in the propelling direction whereby the exertion required in swimming will be reduced and swimming will be made easier, and the object of my improvement is to produce a foot-aid that is relatively simple and of economical form of construction, and convenient and efficient in use, and that particularly is free operating and reliable.

In the accompanying drawing:-

Figure 1 is a plan view of my improved swimmer's foot-aid, as viewed from the top side that is applied to the bottom of the foot of the swimmer.

Figure 2 is a bottom view of the same.

Figure 3 is an end elevation of the same, an alternative position of the wings being shown by broken lines.

Figure 4 is a sectional view on the line 4-4 of Fig. 1.

Figure 5 is a plan view of the blank for the wing structure.

Figure 6 is a plan view of the blank for the hinge plate.

Figure 7 is a plan view of the blank for the stop plate for limiting the inward movement of the wings.

My improved swimmer's foot-aid comprises a foot-plate or base 10 that is adapted to be applied to the bottom of the foot of the swimmer in any approved manner and operatively supported from said plate 10 is an expandible and collapsible wing structure, the latter being composed in the present instance of a pair of wings 11 that are individually connected to said plate 10 by means of a suitable hinge connection.

The foot-plate 10 is fashion-shaped, comprising a shank portion 12 intermediate a heel portion 13 and a sole portion 14 and is provided with a plurality of holes 15 for

attaching means for attaching to the sole of a shoe, as indicated by the broken lines 16, the foot plate being preferably made of narrower width than the shoe and being smaller generally so as to avoid detrimental dragging effect or back resistance.

The border edges of the foot-plate 10 are provided with a downwardly directed flange of appreciable depth that serves as a reinforcement or stiffening means and also serves to enclose and define a pocket that tends to confine and retain a layer of water under pressure conditions. The effect thereof is to reduce water friction as applied to the water that is diverted laterally during the thrust movement.

The wings 11 also have a border-flange 18 that extends along the free edge portion at the outside and ends that cooperates with the hinge structure to be described to enclose and confine a film or layer of water.

The wing structure is secured to the foot-plate 10 along the axial line by means of a set of rivets 19.

Said hinge structure is composed of the two individual wings 11 that have their inner ends opposed and positioned in spaced relation and an intermediate connecting hinge plate 20 that bridges said space, the opposed edges of the said plate 20 and the adjacent wing 11 being connected by means of a hinge connection, as will be described.

Said hinge connection comprises a set of knuckles or hinge-sleeves 22 on the wing 11 that alternate with a set of knuckles or hinge-sleeves 23 on the plate 20, an elongated pivotal pin 24 being extended through the entire series of knuckles.

Thus the hinge structure, as described, is adapted to be assembled by itself complete as a unit and finally connected to the foot-plate 10 by means of the rivets 19.

Constructed as described, the wings 11 are adapted to swing freely relatively to the supporting foot-plate 10 and as the foot of the swimmer is pushed downwardly or outwardly in the water they tend to open out under the pressure of the water, and by having the wings 11 extend appreciably outwardly beyond the borders of the foot the effective area for contacting with the water is increased so as to make more effective the efforts of the swimmer. As the foot is lifted the wings 11 will collapse and close together, so that the resistance to such upward movement is reduced to a minimum.

I find it desirable to positively check such inward or return movement of the wings 11 so that when at the innermost position they will be substantially parallel and at right angles to the foot-plate 10. Thus is avoided a back of the center condition of the wings and they will be ready to open instantly upon a change in direction of movement to the thrusting or pushing direction, such 10 opening being effected by the rush of water between the wings 11.

The means for checking the wings as described comprise on each side a backing edge 25 for abutting with the opposed portion of the inner face of the wing 11, said edge 25 being positioned immediately below the hinge connection 21.

Said backing edges 25 are provided by means of a backing plate 26 and constitute 20 the free edges of a pair of laterally directed flanges 27 at the lateral ends of said plate 26. Intermediate the flanges 27 is a U-shaped supporting body that is composed of the opposed and parallel side walls 28 and 25 a connecting yoke or base 29 intermediate said side walls 28.

Said yoke or base 29 overlays the body portion of the hinge-plate 20 and is held in

place by means of the rivets 19 already mentioned.

The backing plate 26 serves in a general way as a reinforcement of the assembled structure as a whole, and particularly along the longitudinal axis or backbone.

The structure as described is preferably 35 made of sheet metal, particularly aluminum.

Changes in details may be made from the particular forms that are shown. Thus the body portion of the wings may be corrugated to provide reinforcing ribs and permit 40 the use of thinner sheet material.

I claim as my invention:—

A swimmer's foot-aid comprising a longitudinally directed supporting plate, a wing structure on the under side of said plate, 45 and a backing plate on the under side of said wing structure, said wing structure comprising a middle plate and a pair of wings connected individually to the opposite lateral edges thereof, said backing 50 plate having flanges for cooperating with said wings as back-stops, and said middle plate, wings, and backing plate being made of sheet metal.

ALBERT B. JOHNSON.
